DESIGN FOR A BEDSPREAD

Louis E. Mayer, New York, N. Y.

Application June 30, 1937, Serial No. 70,130

Term of patent 3½ years

To all whom it may concern:

Be it known that I, Louis E. Mayer, a citizen of the United States of America, residing in the city of New York, State of New York, have invented a new, original, and ornamental Design for a Bedspread, of which the following is a specification, reference being had to the accompanying drawing, forming part thereof, wherein, the figure is a plan view of a bedspread, showing my new design.

The figure is a complete bedspread with a three sided border, the fourth side being without a border. The black border portion shown beyond the outer edges of the design represents the background on which the fabric was placed to be microphotolithographed.

I claim:

The ornamental design for a bedspread, substantially as shown and described.

LOUIS E. MAYER.
